DOORKNOB BELL

Filed Dec. 8, 1927

James C. Hopkins
INVENTOR.

BY
Charles Clark
ATTORNEY.

UNITED STATES PATENT OFFICE.

JAMES C. HOPKINS, OF NEW YORK, N. Y.

DOOR-KNOB BELL.

Application filed December 8, 1927. Serial No. 238,578.

My invention relates to door knobs and refers more particularly to a door knob bell or alarm.

One object of my invention is to produce a door knob alarm wherein the alarm or bell, together with the mechanism for operating the same is a part of the knob itself.

Another object of my invention consists in a door knob alarm wherein one knob comprises the alarm and the operating mechanism therefor and the other knob contains the push button for operating the same.

It is well known in the art that combinations of door bells and door knobs have been used but none of them contemplate the particular combination of parts and the method of operation utilized in this specific device.

I accomplish this result by means of the mechanism illustrated in the accompanying drawings, wherein similar numerals refer to like parts throughout the several views, in which:—

Figure 1, is an elevation, partly in section, of the device as applied to a door.

Figure 2, is an enlarged view of a side elevation of the plate with the operating mechanism assembled thereon.

Figure 3, is a front elevation of Figure 2.

The door 1, with the lock 2, screwed thereto by the screws 3 and 4, with the bolt 5, and latch 6, has the plate 7, with the boss 8, and the plate 9, with the boss 10; which bosses carry the ends of the knobs in the same manner as in all doors.

The knob 11, is provided with an opening 12, into which slides the head of the rod 13, which rod has a female thread at 15, to engage with the male thread 17, on the extension rod 16, said rods constituting the push button, and the rod 16 also has a stop pin near the end 19 which end is rounded and is adapted to engage with the mechanism for operating the bell.

The extension rod 16 is guided through the hole 20, of the knob 22, and the rod 13, is guided by the hole 21, in the knob 11, and the threaded parts 17 and 15, provide for any adjustment that may be required to suit different thicknesses of doors.

In place of the solid square rod ordinarily used to connect the knobs together, a square tube 23, is used which has a number of threaded openings 24, in which the set screws 25, may fit, these holes providing for any adjustment that may be required to suit different thicknesses of doors.

The knob 22, which contains the bell and the mechanism for ringing the same, is comprised of three main parts, a base which consists of a round stem with a square opening 60 therein to hold the square tube from which stem a cup-shaped piece projects inside of which is a boss or flange or ear 27, adapted to hold by the rivets 28 and 29 a plate 30 and this flange is offset far enough from the centerline of the knob to bring the bell ringing mechanism in the proper position for easy operation.

The plate 30, holding the operating mechanism, has a lug 33, notched out at 34, and 70 threaded at 35, to which the bell 36, shaped to fit over the dish shaped base 37, is screwed by the screw 38, and this bell has a boss in the interior that has a projection 39, adapted to engage with the notch 34, for the purpose 75 of preventing the bell from turning after it is screwed into place.

Upon this plate 30, is pivoted a segment piece 40, by the pivot 41, said segment having an extension 42, which is provided with a 80 hole 43.

This segment meshes with a gear 44, held rotatable, together with an escapement wheel 45, both of which are pivoted to the plate 30 by the pivot 46.

Upon this escapement wheel 45, is mounted a pawl 47, pivoted at 48, to this wheel 45, which pawl has a spring 49, attached thereto, the end of which rests against a pin 50, fixed in the wheel 45.

This pawl engages the gear wheel 44, so that when the segment 40, is moved in the direction of the arrow, shown in Figure 2, the gear will engage with the pawl and carry around the escapement wheel and when the 95 segment is moved backward by the spring 51, connected to the arm 42, through the hole 43, and the lug 52, on the plate 30, through the hole 53 therein, the pawl will ride freely over the gear wheel 44 and the escapement 100 wheel 45 will not move.

The plate 30, also carries an escapement 54, pivoted thereto by the pivot 55, the part 54 carrying a spring piece 56, at the end of which is a ball 57, and the said escapement 105 engages with the escapement wheel 45, so that when the escapement wheel is moved the escapement will vibrate and the ball portion that is arranged adjacent to the bell 36, will ring the bell.

In operation, when the push button 14, is pushed in, it forces the rods 13 and 16 against

the segment 40, causing the gearwheel 44, to revolve and with it the escapement wheel 45, which in turn vibrates the escapement 54, constituting the bell hammer making the bell 5 ring.

When the push button is released, the spring 51, carries all of the mechanism back to its normal position except the escapement wheel which will not move backward because 10 the pawl will not engage with the gear 44.

Having thus described the preferred embodiment of my invention, I do not wish to limit myself to the exact arrangement or construction shown, since it is evident that modifications may be made therein without departing from the spirit of the invention or scope of the claims.

I claim:

1. In a door knob bell, the combination 20 with a knob countersunk for holding an adjustable push button with a stop pin passing into another knob comprised of a base and a bell and an angle plate holding a pivoted lever resiliently held against said button and 25 a bell ringing mechanism operable by the said push button mounted on said plate.

2. In a door knob bell, the combination

with a knob carrying a centrally operable push button with a pin therein and a knob 30 with a base supporting an angular plate carrying a pivoted lever with a spring and a bell ringing mechanism and a bell.

3. In a door knob bell, the combination 35 with a knob carrying a centrally operable adjustable push button provided with a stop pin and a knob comprised of a saucer shaped base having an offset inside flange, holding an angular plate supporting a pivoted lever with a spring and gear teeth connected to a bell and a bell ringing mechanism. 40

4. In a door knob bell, the combination 45 with a knob carrying a centrally operable adjustable push button with a stop pin, a knob comprised of a saucer shaped base having an offset inside flange carrying a plate holding a centrally pivoted lever provided with a spring on one end, the other end provided with gear teeth connected to a gear operably connected to an escapement wheel by a pawl, an escapement carrying a bell hammer, and a bell.

Signed at New York, county and State of New York, this 6th day of Dec., 1927.

JAMES C. HOPKINS.
